BIN DIVIDER CONSTRUCTION

Howard S. Ingelson, Glendale, Calif.

Application June 5, 1953, Serial No. 359,919

3 Claims. (Cl. 312—140.3)

This invention relates to store equipment and particularly to an improved divider construction for counter bins and the like whereby the counter surface may be readily divided into bin areas of the desired sizes for segregation and display of goods.

In variety stores and the like having a great variety of inexpensive goods, the counter surfaces are divided into shallow bin areas for the different items and for efficient display, it is desirable that each such bin be only so large as to contain a quantity of the item as will require only occasional replenishing to the end that the greatest possible number of items may be displayed on a given counter area surface. Heretofore, the most common arrangement has been to use heavy glass strips as bin dividers; said strips being held in place by boards of the desired bin areas; the adjacent area defining boards being spaced from each other only sufficiently to form divider receiving slots for the glass strips. This necessitates carrying a large number of such bottom boards and the accompanying glass strips in various lengths to provide means for changing the bin arrangements on the counters in response to seasonal and other changes in merchandise display. The stock thus carried is not only heavy and bulky, but also the changing of bin arrangements is a time-consuming operation.

With the foregoing considerations in mind, it is an object of the invention to provide a counter bin divider construction which is constructed and arranged for ready variation of the bin areas without the necessity of clearing the entire counter area for reinstallation of a different bin arrangement.

Another object of the invention is to provide a counter bin construction in which at least part of the partition members are constructed and arranged for selective engagement with other partition members for ready variation of the bin sizes without change in the bottom board arrangement.

A further object of the invention is to provide a counter bin partition construction comprising primary divider elements having means for selective engagement with secondary divider elements for selective variation of bin sizes.

Still another object of the invention is to provide a counter bin divider construction including a divider element formed of vertically disposed, rigid material having vertical corrugations therein affording receiving slots or sockets for other divider elements.

With the foregoing objects in view, together with such other objects and advantages as may subsequently appear, the invention resides in the parts, and in the construction, combination, and arrangement of parts disclosed, by way of example, in the following specification of certain modes of execution of the invention; reference being had to the accompanying drawings which form a part of said specification and in which drawings:

Fig. 1 is a top perspective view of a portion of a counter top showing the invention applied thereto,

2

Fig. 2 is an enlarged, fragmentary sectional view taken on the line 2—2 of Fig. 1.

Fig. 3 is a perspective view of a portion of the primary divider element shown in Figs. 1 and 2.

5 Fig. 4 is a top plan view of the divider element shown in Fig. 3.

Fig. 5 is a perspective view of a second form of primary divider element.

10 Fig. 6 is an exploded view of the component parts of the divider element shown in Fig. 5, and

Fig. 7 is a bottom plan view of the partition portion of the divider element shown in Figs. 5 and 6.

Referring first to the form of the invention shown in Figs. 1, 2, 3 and 4, there is shown in Figs. 1 and 2 a counter top C having a back board B and a front board F extending longitudinally thereof which together with end boards (not shown) form the counter top into a large shallow bin area to be divided into smaller areas by suitable adjustable divider means for reception of the

15 various merchandise items to be displayed therein. Heretofore, the most commonly employed divider means has been the glass strip elements above described, and the present invention is directed to the illustrated improved means for effecting such division of the counter top area.

20 25 The present invention includes a primary divider element 1 formed of sheet metal or plastic strip and including a vertically disposed portion 2 which is vertically corrugated with resultant formation of divider receiving

30 35 grooves on each side thereof, an integrally formed laterally extending foot portion 3 longitudinally co-extensive with the vertical portion 2 and a series of tab elements 4 punched out of the foot portion 3 and bent to extend laterally in the plane of the foot portion from the opposite side of the vertical portion 2. The primary divider element is cut to lengths to extend from the back board to the front board of the counter top and the lengths are positioned on the counter top in spaced relation by false bottom boards 6 which overlie the foot portions and tab elements, forming the counter top into a series of bin

40 45 areas of widths determined by the widths of the bottom boards and of length extending from the back board to the front board of the counter. These bin areas are then further subdivided by secondary divider members 7 comprising rigid strips of wood or other material engaging

50 55 oppositely disposed corrugations in the primary divided strips and resting on the upper surface of the false bottom board 6 as shown in Fig. 1. Since the corrugations are closely spaced, the areas defined by the parallel primary members may be readily varied to suit different merchandise demands by placement of the secondary divider strips. Thus it is necessary only to carry a few

bottom boards of various widths other than those actually in use so that the width of bins may be varied, together with corresponding secondary dividers for those bottom boards. The primary divider elements are all of the same length and therefore it is necessary only to carry a few extra lengths to supply the need when more are needed. Attention is especially called to the fact that the corrugations stiffen the strip against flexure along lines longitudinal of the strip and that the foot portion stiffens the strip against flexure transversely of the strip.

60 65 The primary divider elements are simple to manufacture and require little material and consequently are economical to produce. Preferably the primary divider elements are furnished in long lengths to be cut to fit the counters by the purchaser.

Referring next to the form of the invention shown in Figs. 5, 6 and 7, the divider element is shown as fabricated from two separate elements. The base portion 8 is formed in the same general manner as the foot portion 3 of the first form of the invention and including a lateral flange portion 9, a series of oppositely extending tabs

10 formed from the flange 9 and a vertically disposed divider supporting portion 11. The divider component comprises a transversely corrugated strip of metal or plastic strip 12 having a series of centrally disposed, longitudinally aligned slits 13 formed in one edge thereof; said slits being sufficiently narrow to tightly grip the divider supporting portion 11 of the base portion 8 as shown in Fig. 5. This divider element is used in the same manner as above described in connection with the first described form. It has advantages in that the divider element is more economically formed by a rolling process and in that different heights of divider element can be more readily stored when not in use. Further, the height of divider may be changed when desired, without removal of the base element unless at the same time the lateral dimensions of the bin are to be changed.

While the invention is primarily useful as a counter bin divider, it is also useful in dividing storage drawers and the like. Consequently, any references to counter bins will be understood to include all areas for which the invention may be used as a partition means.

While in the foregoing specification there has been disclosed certain embodiments of the invention, it is appreciated that in the light of such disclosure modifications will suggest themselves to others skilled in the art. Therefore, the invention is not to be deemed to be limited to the exact embodiments disclosed, and it is to be understood that the invention embraces all such modifications in the parts, and in the construction, combination and arrangement of parts as shall come within the purview of the appended claims.

I claim:

1. In a counter bin divider construction, a pair of spaced, parallel primary divider elements extending between opposite vertical walls on a counter top and comprising oppositely disposed walls of a bin; each of said divider elements comprising a vertically disposed portion having a plurality of vertical corrugations forming divider element receiving grooves on both sides thereof extending from the upper edge thereof to a point adjacent the counter top and a longitudinally co-extensive foot portion extending horizontally from the lower edge of the corrugated portion and resting on the counter top, a false bottom board forming the bottom of the bin and overlying the foot portions of said divider elements, and a secondary divider element extending transversely to and between said primary divider elements and held in vertical position by engagement of the ends thereof with a pair of concavely opposed corrugations in said primary divider elements and forming at least a third side of said bin.

2. In a counter bin divider construction, a pair of spaced, parallel primary divider elements extending between opposite vertical walls on a counter top; each of said primary divider elements having a vertically disposed portion having at least one vertically disposed corrugation extending from the upper edge thereof to a point adjacent the counter top and having a longitudinally co-extensive horizontally disposed foot portion resting on the counter top; said corrugations being transversely opposite and concavely opposed to each other, a false bottom board forming the bottom of the bin and overlying the foot portions of said divider elements, and a secondary divider element extending between said primary divider elements and having its ends engaging said corrugations and forming another side of a bin defined by said primary divider elements.

3. In a counter bin divider construction, a pair of primary divider elements disposed in spaced, parallel relation on a counter top and extending between opposite vertical walls on a counter top; each of said primary divider elements comprising a strip of metal having a vertically disposed partition forming portion and a longitudinally co-extensive horizontally disposed foot portion resting on the counter top; said partition forming portion being provided with a plurality of vertically disposed corrugations extending on both sides thereof from the upper edge thereof to a point adjacent said foot portion, a false bottom board forming the bottom of the bin and overlying the foot portions of said divider elements, and a secondary divider element comprising a strip of rigid material disposed transversely to and extending between said primary divider elements; said secondary divider element being held in vertical position and against lateral or longitudinal displacement by engagement of the ends thereof with a pair of concavely opposed corrugations in said primary divided elements and forming at least a third side of the bin.
